UNITED STATES PATENT OFFICE.

SIDNEY V. JAMES, OF NIAGARA FALLS, NEW YORK, ASSIGNOR TO WM. A. ROGERS, LTD., OF NIAGARA FALLS, NEW YORK.

DESIGN FOR A SPOON OR SIMILAR ARTICLE.

Application filed May 8, 1925. Serial No. 13,359. Term of patent 3½ years.

To all whom it may concern:

SIDNEY V. JAMES, a citizen of the United States, and resident of Niagara Falls, county of Niagara, and State of New York, and whose post-office address is care of Wm. A. Rogers, Ltd., Niagara Falls, N. Y., has invented a new, original, and ornamental Design for Spoon or Similar Article, of which the following is a specification, reference being had to the accompanying drawing, forming a part thereof.

Referring to the drawing:

Figs. 1 and 2 are opposite face views of a spoon or similar article showing my new design.

Fig. 3 is a cross section on the line 3—3 of Fig. 2.

I claim:

The ornamental design for a spoon or similar article as shown.

SIDNEY V. JAMES.
